UNITED STATES PATENT OFFICE.

LEWIS E. GREEN, OF CONNERSVILLE, INDIANA, ASSIGNOR TO GREEN BROS., OF CONNERSVILLE, INDIANA.

FAUCET FOR DISPENSING SODA-WATER.

1,159,836.

Specification of Letters Patent.

Patented Nov. 9, 1915.

Application filed March 26, 1915. Serial No. 17,299.

To all whom it may concern:

Be it known that I, LEWIS E. GREEN, a citizen of the United States, residing at Connerville, Fayette county, Indiana, have 5 invented certain new and useful Improvements in Faucets for Dispensing Soda-Water, of which the following is a specification.

This invention pertains to that class of 10 soda-water faucets which have two nozzles, one for the delivery to the glass of the bulk of the liquid upon the syrup previously deposited in the glass and the other a smaller one for mixing and agitating the contents 15 of the glass and producing the foam, and the invention relates particularly to features of construction aimed at positiveness of performance, accessibility of parts and durability of structure.

20 My invention will be readily understood from the following description taken in connection with the accompanying drawings in which:—

Figure 1 is a front elevation of the faucet: Fig. 2 vertical sections of the same in diverse planes represented by lines *a*, *b* and *c* of Figs. 1, 3, 4, 5, and 6: Fig. 3 a front elevation, part vertical section in the plane of line *d* of Figs. 2, 4 and 5: Fig. 4 a sectional plan in the plane of line *e* of Figs. 1, 2 and 3: Fig. 5 a plan of the removable housing-base, one of the valve-levers appearing in section in the plane of line *e* of Figs. 1, 2 and 3: and Fig. 6 a vertical section of 35 the housing-base in the plane of line *f* of Figs. 2, 4 and 5.

In the drawings:—1, indicates the general structure which I will term the head: 2, a neck connected with the upper portion 40 of the head and adapted to be connected with the fountain on which the faucet is to be employed: 3, an inlet leading to a passage through the neck and into the upper part of the head to admit 45 the soda-water from the fountain to the head: 4, a chamber in the upper part of the head this chamber communicating with inlet 3: 5, a removable screw-plug closing the upper end of chamber 4: 6, the passage through 50 the neck, leading from inlet 3 to chamber 4: 7, a housing-base removably secured to the base of the head: 8, a chamber in the housing-base, open at its top, this chamber being at one side of the center of width of the 55 head, the head being circular in horizontal

cross section: 9, a second similar chamber in the housing-base at the opposite side of the center of width of the head: 10, a vertical port in the head extending from chamber 4 in the top of the head to chamber 8 in the 60 housing-base: 11, a similar vertical port extending from top chamber 4 to chamber 9 in the housing-base: 11^a, a large vertical chamber in the front portion of the head, extending from the floor of top chamber 4 65 to the base of the head: 12, valves, one seated downwardly at the upper end of each of ports 10 and 11 and normally cutting off any outflow from top chamber 4: 13, the valve-stem of that one of valves 12 which pertains 70 to base chamber 8, this stem projecting downwardly from its valve through port 10 and into base chamber 8: 14, a similar valve-stem pertaining to the other valve: 15, a large nozzle secured upon a boss projecting 75 downwardly from the housing-base, this nozzle being open at its lower end: 16, a small nozzle-tube disposed concentrically within nozzle 15 and having its upper end screwed into the housing-base: 17, an aperture leading from chamber 8 in the housing-base to the interior of large nozzle 15, outside the nozzle-tube 16: 18, an aperture leading from chamber 9 in the housing-base to the interior of small nozzle-tube 16: 19, a 80 horizontal pivot mounted in the housing-base and crossing chamber 8 therein: 20, a similar pivot crossing chamber 9: 21, a bellcrank lever mounted within chamber 8 on pivot 19, one arm of this lever standing vertically while the other arm projects under the vertical stem 13: 22, a similarly arranged bellcrank lever disposed in chamber 9 and mounted on pivot 20, one of the arms of this lever engaging below valve-stem 14: 95 23, a spring at the lower end of each valve-stem and acting downwardly on collars on the lower ends of the stems and serving to normally press the two valves to their seats: 24, plungers sliding horizontally in the 100 housing-base at right angles to the common axis of pivots 19 and 20, these plungers having rear ends in engagement with the fronts of the vertical arms of the bellcrank levers: 25, horizontal pins, parallel with 105 pins 19 and 20, mounted in the forward portion of the housing-base: 26, vertical levers mounted on these pins and projecting up into recess 11^a in the head to a point near the top of that recess, the bases of these 110

levers being inwardly beyond plungers 24: 27, a push-button secured to the upper end of each of the levers 26, these push-buttons projecting out forwardly and loosely 5 through apertures in the front wall of the head: 28, a vertical arm mounted on pin 25 at the outer side of each of vertical levers 26, these arms being unified with and working with their respective vertical levers: 29, 10 screws passing through arms 28 and into vertical levers 26 and serving to bind the arms to their levers: 30, an adjusting screw threaded horizontally through each arm 28, above its screw 29, and in alinement with 15 its respective plunger 24, the rear ends of these screws engaging the front end of their respective plungers, that portion of the arms 28 above screws 30 being slotted axially of the screws, so that the action of screws 29 20 in binding arms 28 to their vertical levers may pinch upon screws 30: and 31, a circular shell inclosing the housing-base, this shell having its top rim engaging the base of the head and having the bottom centrally 25 perforated and engaging a flange on nozzle 15, whereby the screwing of the nozzle to place upon the housing-base serves to secure the shell to the base of the head.

Normally the two valves are closed, and 30 held so by springs 23, the push-buttons being in protruded position. The liquid coming from the fountain is maintained under pressure in chamber 4, this pressure serving, in addition to the springs, in holding the 35 valves shut and in closing them when they are open. If, now, the left-hand push-button 27 be pushed in it will, in an obvious manner, bring about the opening of the left-hand valve, thus permitting liquid to flow through 40 port 10 and into chamber 8 and thence, through aperture 17, to and through the large outer nozzle and into the glass. Screw 30 pertaining to the left-hand lever having been so adjusted that valve 12 will open to 45 such limited extent that the liquid in going to the glass will do so without such violence of discharge from the nozzle as will produce serious foaming. This permits the glass to be filled to the proper extent with 50 liquid, in comparatively quiescent condition, whereupon the push-button being released, valve 12 automatically closes. The right-hand push-button is then to be operated, bringing about the opening of the 55 right-hand valve, thus permitting the liquid to flow through port 11 into chamber 9 and through aperture 18 to and through the inner nozzle 16 and to the glass. The adjusting screw pertaining to the right-hand 60 lever should be so adjusted as to open the right-hand valve to such extent that the liquid will spurt from nozzle 16 into the liquid in the glass with such violence as to bring about the proper foaming as well as the 65 thorough mixing of the liquid with such

syrup as may have been previously placed in the glass.

In the particular construction illustrated the valve-stems are provided with guide-wings, and plungers 24 operate through 70 packing glands. Screws 29 serve in pinching arms 28 on the adjusting screws and preventing their getting out of adjustment.

By unscrewing outer nozzle 15 from the housing-base shell 31 may be removed thus 75 exposing the mechanism in the front of the housing-base and permitting the adjustment of screws 30. By removing the screws which secure the housing-base to the head, and by removing the push-buttons, the supply of 80 liquid from the fountain having of course been cut off, the housing-base with its lever and arm mechanism may be removed downwardly and all the parts carried by the housing-base may be inspected or adjusted or disassembled. By removing screw-plug 5 and removing the collars from their stems the 85 valves may be removed upwardly and the springs may be removed downwardly. The construction is such that there need be no 90 gaskets.

I have, in exemplifying my invention, illustrated the best form within my present contemplation but the invention will obviously lend itself to modifications.

95

I claim:

1. A dispensing faucet comprising, a head provided with a top chamber and with an inlet to such chamber and a pair of base chambers and with a pair of vertical ports 100 placing the top chamber in communication with the base chambers, an inner nozzle communicating with one of said base-chambers, an outer nozzle communicating with the other base-chamber, a valve seated downwardly in the upper end of each of said ports, a stem projecting downwardly from each valve through the port controlled by that valve and into one of the base-chambers, a pair of push-buttons at the face of 110 the head, and mechanism operatively connecting each push-button with one of the valve stems, combined substantially as set forth.

2. A dispensing faucet comprising, a head 115 provided with a top chamber and with an inlet to such chamber and a pair of base-chambers and with a pair of vertical ports placing the top chamber in communication 120 with the base-chambers, an inner nozzle communicating with one of the said base-chambers, an outer nozzle communicating with the other base-chamber, a valve seated downwardly in the upper end of each of said ports, a stem projecting downwardly from 125 each valve through the port controlled by that valve and into one of the base-chambers, a pair of push-buttons at the face of the head, mechanism operatively connecting each push-button with one of the valve 130

stems, and a housing-base forming a separable part of said head and containing said base-chambers, combined substantially as set forth.

5 3. A dispensing faucet comprising, a head provided with a top chamber and with an inlet to such chamber and a pair of base-chambers and with a pair of vertical ports placing the top chamber in communication with the base-chambers, a valve seated downwardly in the upper end of each of said ports, a stem projecting downwardly from each valve through the port controlled by that valve and into one of the base-chambers, a pair of push-buttons at the face of the head, mechanism operatively connecting each push-button with one of the valve stems, an inner nozzle secured at the base of the head and communicating with one of 10 said base-chambers, an outer nozzle removably secured at the base of the head and having an upwardly presenting flange, and a cup shaped shell having its floor in engagement with said flange and its rim in engagement with the base portion of the head, combined substantially as set forth.

4. A dispensing faucet comprising, a head provided with a top chamber and with an inlet to such chamber and a pair of base-chambers and with a pair of vertical ports placing the top chamber in communication with the base-chamber, a vertical chamber forward of said ports, an inner nozzle communicating with one of said base-chambers, an outer nozzle communicating with the other base-chamber, a valve seated downwardly in the upper end of each of said ports, a stem projecting downwardly from each valve through the port controlled by 15 that valve and into one of the base-chambers, a pair of levers disposed in said vertical chamber and having their bases pivoted below said chamber, a push-button carried by the upper end of each of said levers and protruding forwardly through the front wall of said vertical chamber, and mechanism operatively connecting the lower portion of each lever with one of the valve stems, combined substantially as set forth.

50 5. A dispensing faucet comprising, a

head provided with a top chamber and with an inlet to such chamber and a pair of base chambers and with a pair of vertical ports placing the top chamber in communication with the base-chambers, a vertical chamber 55 forward of said ports, an inner nozzle communicating with one of said base-chambers, an outer nozzle communicating with the other base-chamber, a valve seated downwardly in the upper end of each of said ports, a stem projecting downwardly from each valve through the port controlled by that valve and into one of the base-chambers, a pair of levers disposed in said vertical chamber and having their bases pivoted below said chamber, a push-button carried by the upper end of each of said levers and protruding forwardly through the front wall of said vertical chamber, a bellcrank lever pivoted in each of said base-chambers, 60 each lever having one of its arms engaging below one of said valve stems, a plunger arranged to reciprocate horizontally and disposed in front of each bellcrank lever and having its rear end in engagement with an 65 arm of an appropriate one of the said levers, and a pushing means carried near the base of each push-button lever and adapted to engage the front end of the appropriate plunger, combined substantially as set forth.

6. A dispensing faucet comprising in its valve-operating mechanism, a lever pivoted at its base and having a push-button on the upper end of said lever, an arm disposed alongside said lever and secured to it and 85 provided with an end slotted in the plane at right angles to the pivot of the lever, an adjusting screw threaded through the arm at its split portion, a screw engaging the arm and lever and serving to secure the arm to 90 the lever and to pinch the split portion of the arm upon the adjusting screw, and a reciprocating plunger engaged by said adjusting screw, combined substantially as set forth.
